(57) **CLAIM**

The ornamental design for a tube, as shown and described.

DESCRIPTION

FIG. 1 is a front perspective view of my new design;

FIG. 2 is a front elevational view of my new design, the rear
elevational side view being identical;

FIG. 3 is a side elevational view of one side of my new design,
the opposite elevational side view being identical;

FIG. 4 is a top plan view thereof; and,

FIG. 5 is a bottom plan view thereof.

The broken lines immediately adjacent the shaded areas represent
the bounds of the claimed design while all other broken
lines are directed to environment and are for illustrative pur-
poses only; the broken lines form no part of the claimed
design.
